TIRE

William W. Wolford, Akron, Ohio, assignor to The Good-year Tire & Rubber Company, Akron, Ohio

Filed Jan. 3, 1972, Ser. No. 215,259

Term of patent 14 years

Int. Cl. D12—15

U.S. Cl. D90—20 R

The figure is a perspective view of a tire showing our new design, it being understood that the design is repeated throughout the circumference of the tire, the opposite side being substantially the same as that shown.

I claim:

The ornamental design for a tire, substantially as shown and described.
